UNITED STATES PATENT OFFICE.

HENRY R. FRISBIE, OF NEWARK, ASSIGNOR TO THE EASTWOOD WIRE MANUFACTURING COMPANY, OF BELLEVILLE, NEW JERSEY.

STAND-PIPE FOR BOILERS.

SPECIFICATION forming part of Letters Patent No. 551,817, dated December 24, 1895.

Application filed August 15, 1895. Serial No. 559,430. (No model.)

To all whom it may concern:

Be it known that I, HENRY R. FRISBIE, a citizen of the United States, and a resident of Newark, in the county of Essex and State of New Jersey, have invented certain new and useful Improvements in Stand-Pipes for Boilers, of which the following is a specification.

My invention relates to an improvement in stand-pipes and gage-cocks therefor for boilers; and it consists in certain details of construction to be more fully set forth and described in the following specification, and such features believed to be new and novel particularly pointed out in the claims.

To enable others to understand my invention, reference is had to the accompanying drawings, in which—

Figure 1 represents a front elevation of the stand-pipe, central sectional view of a gage-cock connected therewith, broken view of the outer shell of the stand-pipe at the point of such connection, and broken view of one of the water-gage-glass protecting side rods. Fig. 2 is an upper plan view of the stand-pipe, looking in the direction of arrow *a* of Fig. 1. Fig. 3 is a vertical central section of the stand-pipe, valves, and water-glass connections, and broken view of the boiler-connecting pipes, looking in the direction of arrow *b* of Fig. 1. Fig. 4 is a detail side elevation of the upper valve and water-glass connection, broken view of the gage-glass, and broken view of the valve-operating lever. Fig. 5 is a detail view of one of the valve-body plugs having a threaded end adapted to screw into the stand-pipe and a projecting hollow column to support the water-gage-glass connection.

Its construction and operation are as follows:

1 is the stand-pipe, having holes 2-3 4 for the gage-cocks, presently to be more fully explained, and 5, 6, 7, and 8 pipe connections leading therefrom, the two former connecting directly with the boiler.

As the construction of both of the upper and lower valve connections is substantially the same, such features, therefore, as are alike will, to avoid confusion, be designated by the same figures of reference.

9, Figs. 3, 4, and 5, are the upper and lower

valve-plug bushings, whose threaded ends 9^a are screwed into threaded holes near the top and bottom of the stand-pipe 1. The outer projecting end has the reduced central portion 10, whose cylindrical surface is pierced with the elongated holes or openings 11 communicating with the interior 12. The narrow cylindrical seats 10^a support the rotatable sleeves 13 13^a, so that when such sleeves are mounted thereon the opening or chamber 14 is formed, which opening or chamber surrounds the reduced central portion 10 for the purpose to be hereinafter more fully described.

Projecting from the body portion of the sleeves are seen the hollow exteriorly-threaded nipples 15, whose interior 16 communicates with the interior of the sleeves. These nipples are provided with the usual retaining-nuts 17 for holding the water-gage glass 18 in position. The ends of this glass are inserted into the holes 16 of the said nipples, and, as usual in such cases, holes are formed in the upper surface of the retaining-nuts 17 to freely admit such glass and not allow the metal to come in contact therewith.

To support the glass and prevent its dropping too far within the lower sleeve I have provided the metal seat 19, whose upper overhanging lips 20 rest on the top of the nipple 15, and whose inwardly-projecting seat 21 will support the lower end of the glass tube.

Heretofore it has been the custom in constructing stand-pipes to make the valves with rigid glass-gage connections, so that it was exceedingly difficult and well-nigh impossible to screw the valves into the stand-pipe so that the holes for the glass gage would be in perfect alignment with each other, and when the retaining-nuts were sufficiently tightened to prevent leakage the glass would be so strained and cramped as to cause it to break.

In my improved construction the valve-plugs 9 can each be firmly seated in the stand-pipe. Then the sleeves 13 can be rotated on their supports until the gage-holes 16 are brought in perfect alignment with each other, and when in that position are firmly held against the shoulders 9^b of the valve-plug by means of the stuffing-box bushing 22, whose shoulder 22^a abuts the outer face of the ro-

tatable sleeve 13. The outer or stuffing-box end 22^b of this bushing 22 is provided with the follower 23 and nut 24.

25 25^a are spindles passing through each of 5 the stuffing-box bushings, whose threaded portion 26 engages the interiorly-threaded portion thereof.

27 are exteriorly-threaded valve-seat bushings and are screwed into the base of the 10 valve-plugs 9, which valve-seat bushings are provided with the lugs 27^a for convenience in screwing them to their seat. These valve-seat bushings carry the valves 28, whose wings 28^a loosely fit therein and engage with the stems 15 26^a of the spindles 25 25^a. The inner portions of said bushings furnish seats for the said valves. 29 are caps or plugs screwed into the inwardly-projecting ends thereof, and these caps have each a central hole to operatively 20 support the stems 28^b of the valves 28.

29^a are transverse holes in the projecting ends of the bushings 27, which holes operate to prevent dirt and other foreign matter gaining free access to the valve-seats.

25 30 and 31 (see also Fig. 1) are levers rigidly attached to the projecting ends of the upper and lower valve-spindles 25 and 25^a.

32 is a flat rod pivotally connecting said levers.

30 33 is an operating-lever also rigidly attached to the lower valve-spindle having a hole 33^a therethrough, in which hole a rod, cord or chain may be placed for operating the device. On the upper valve-spindle is rigidly mounted 35 the indicating-hand 34.

35 and 36 represent the guide-rods on each side of the gage-glass.

Mounted on the top of the stand-pipe column 1 (see also Fig. 2) is the name-plate 37, whose 40 right and left branches have stamped or cast thereon the words "Open" and "Shut," which, in conjunction with the hand 34, will indicate the position of the upper and lower valves leading from the interior of the stand-pipe 45 column to the upper and lower open ends of the gage-glass. When, therefore, the hand is in the position shown in Fig. 1, the valves leading to the gage-glass are closed, thus shutting off all communication with the boiler, so 50 that the glass may be removed, cleaned or otherwise dealt with or such other work performed outside the stand-pipe as may be found necessary.

To allow sufficient vertical and horizontal 55 accommodation to the name-plate 37 when the rotary sleeves 13 are being adjusted to bring the gage-glass holes 16 in vertical alignment with each other, and also when the valve-plugs 9 are screwed against the side of 60 the stand-pipe column 1, I prefer to construct the name-plate in two parts, as seen at Fig. 2. The adjusting-plate 38 has the oblong hole 38^a therein, which hole embraces the stud 39 projecting from the upper rotatable sleeve, 65 and when the upper and lower sleeves are properly adjusted, as before mentioned, the

clamping-nut 40 secures the bracket to such sleeve. For the horizontal adjustment of the name-plate 37 the elongated holes 41 are formed in the end of the adjusting-plate 38 70 with screws 42 for securing the said plate firmly to the terminal 37^a of the branches 37^b of the name-plate.

43 is a nipple on the under side of the rotatable sleeve 13^a whose threaded end is 75 surrounded by the flanged nut 44 holding the swivel connection 45 to carry off the drip.

The steam or water from the interior of the stand-pipe column 1 will, when the valves are opened, as before mentioned, pass through 80 the holes 29^a, thence through the central passages of the valve-seat bushings 27 and into the chamber 12 of the valve-plugs 9, thence through the elongated apertures 11 to the circumferential chambers 16, and into each end 85 of the gage-glass.

I prefer to make the threads on the valve-spindles double, so that the valves may be opened with but little movement of said spindles. 90

A stand-pipe column constructed as above described is not only cheaper to make, but much more efficient and reliable than the devices heretofore used for the purpose. The valves are closed by the pressure within the 95 stand-pipe column, so that the upper and lower spindles 25 and 25^a, whose reduced inner free ends operate such valves to open them, can be removed without shutting off the boiler-pressure. Besides, the upper and lower valve 100 and gage-glass connections being made in several parts can be readily replaced by other parts when needed. In a word, the whole construction is readily put together or taken apart or adjusted, as the case may be. 105

Another feature in connection with my improved stand-pipe column is the improved gage-cock, one only being shown at Fig. 1, it being understood, however, that two others are attached to the upper holes 2 and 3, 110 as shown at Fig. 3.

46 is a nipple whose reduced threaded end 46^a is a construction similar to the valve-bushings 27 before mentioned—viz., the valve 47 rests on a valve-seat formed at the bottom of the chamber 48, the mouth of which chamber is closed by the screw-cap 49, the valve-stem 47^a being operatively placed in a central hole in such cap, the wings 47^b of the said valve resting in the hole 46^c of the nipple 46. 120

50 is a discharge-nozzle whose reduced threaded end 50^a is screwed into the open mouth 46^d of said nipple. The valve-spindle 52 has on its inner end the valve 52^a and stem 52^b, which stem rests against the end of the wing 47^b of the valve 47. A valve-seat is provided in the end 50^a of the nozzle for the valve 52^a, while the wings 52^b of said valve rest in a centrally-arranged hole of the inner threaded end of such nozzle. The outer cylindrical portion of the spindle 52 passes through a hole in the end wall 50^b of said nozzle and 130

through the stuffing-box end 50^c, which end is provided with the follower or gland 53.

The handle 54 is bifurcated or forked on its inner end, so as to form two ears, one, 54^a, only being shown. These ears straddle the stuffing-box end of the discharge-nozzle and are operatively mounted on the pin 55.

54^b is a bridge spanning the open space between the ears of the handle 54 and is integral therewith. This bridge is located about on a line with the pivotal point or pin 55, and is adapted, when the valves are closed, to rest against the under side of the stuffing-box end 50^c of the nozzle 50, so as to keep the handle 54 in a horizontal position.

56 is a forked projection located between the ears of the said handle and integral therewith, which fork embraces the valve-spindle 52. 52^d are collars provided on the outer end 20 of this spindle to be engaged by the forked projection 56 in operating the valves. Its operation is as follows: In the drawings the valves are represented as closed. When, therefore, it is desired to test the contents of 25 the stand-pipe, the handle is raised in the direction indicated by arrow *c*, which operation will cause the inner face of the fork 56 to act against the outer face of the inner collar on the valve-spindle 52 and open both 30 valves, the steam or water passing out of the opening *d* of the nozzle 50. Releasing the handle will cause it to drop by its own weight, while the pressure within the stand-pipe will force the valves against their seats.

35 The advantage of a gage-cock constructed as above described lies in the readiness and ease with which it can be opened and closed, and the several parts can be readily removed and cleaned of dirt or other foreign matter liable to clog the operating parts under pressure. Besides, the arrangement of the inner valve 40 48 is such that little dirt can reach the valve-seats, and what does is readily and easily removed.

45 Having thus described my invention, what

I claim as new, and desire to secure by Letters Patent, is—

1. In a stand pipe for boilers, of the character described, comprising in combination, column 1; valve - plug bushings 9 having 50 threaded ends 9^a adapted to be screwed into holes in the face of such column, as shown; the hollow projecting ends of such bushings having outlets 11; reduced portions 10; journals 10^a; rotatable sleeves 13, 13^a mounted 55 thereon; threaded nipples 15 projecting from said sleeves to receive the ends of the gage glass; retaining nuts therefor; seat 19, as shown, to support the lower end of said glass; valve seat bushings 27 screwed into the base 60 of the said valve-plug bushings; valves therefor; the projecting inner ends of said valve-seat bushings having inlet holes 29^a; caps 29 for closing the open mouth of said bushings and, also, to support the valve stems; stuffing- 65 box bushings screwed into the said valve-plug bushings; valve spindles 25, 25^a, as shown, having reduced inner ends to engage the valves, for the purpose described, operating levers connecting the two valve spindles, as 70 set forth.

2. The combination with the stand-pipe column; valve-plug bushings; rotatable sleeves mounted thereon; water glass connected therewith; valve-spindles, as shown; operating levers and connections therefor; indicating hand on one of said spindles; of a name plate mounted upon a stud of the upper sleeve, and means substantially as shown for adjusting such plate relative to the position of said 80 sleeves and means for securing them in a fixed position, for the purpose set forth.

Signed at Newark, in the county of Essex and State of New Jersey, this 17th day of July, A. D. 1895.

HENRY R. FRISBIE.
